(57) **CLAIM**

The ornamental design for a step for a telehandler, as shown and described.

DESCRIPTION

FIG. 1 is a left side perspective view of a step for a telehandler, according to the inventor;

FIG. 2 is a right side perspective view of the step for a telehandler illustrated in FIG. 1;

FIG. 3 is a front view of the step for a telehandler illustrated in FIG. 1;

FIG. 4 is a back view of the step for a telehandler illustrated in FIG. 1;

FIG. 5 is a left side view of the step for a telehandler illustrated in FIG. 1;

FIG. 6 is a right view of the step for a telehandler illustrated in FIG. 1;

FIG. 7 is a top view of the step for a telehandler illustrated in FIG. 1; and,

FIG. 8 is a bottom view of the step for a telehandler illustrated in FIG. 1.

The broken lines shown in the drawings illustrate portions of the step for a telehandler that form no part of the claimed design.
